DESIGN FOR A NIGHT LIGHT

Harold G. Tracy, Detroit, Mich.

Application September 14, 1946, Serial No. 133,318

Term of patent 14 years

(Cl. D48—20)

To all whom it may concern:

Be it known that I, Harold G. Tracy, a citizen of the United States, residing at Detroit, in the county of Wayne and State of Michigan, have invented a new, original and ornamental Design for a Night Light, of which the following is a specification, reference being had to the accompanying drawing, forming part thereof.

In the drawings:

Figure 1 is a side elevation of a night light, showing my new design;

Figure 2 is a top plan view of the night light shown in Figure 1; and

Figure 3 is a perspective view of the night light shown in Figure 1.

I claim:

The ornamental design for a night light, as shown.

HAROLD G. TRACY.
